[57] CLAIM

The ornamental design for a tire, as shown and described.

DESCRIPTION

FIG. 1 is a perspective view of a tire showing my new design, it being understood that the tread pattern is repeated throughout the circumference of the tire, the opposite side being substantially the same as that shown; FIG. 2 is a front elevation view thereof;

FIG. 3 is a side elevation view thereof on a reduced scale; and

FIG. 4 is an enlarged, fragmentary front elevation view thereof.

FIG. 1

FIG.2

FIG. 3
